SEWING MACHINE

Andrew B. Clayton, Union, N. J., assignor to The Singer Manufacturing Company, Elizabeth, N. J., a corporation of New Jersey

Original application August 29, 1941, Serial No. 408,701. Divided and this application March 24, 1943, Serial No. 480,277

6 Claims. (Cl. 112—248)

This application is a division of my pending United States patent application Serial No. 408,701, filed Aug. 29, 1941.

This invention relates to sewing machines and it has as an object to provide an improved mounting for the cam-disk of a rotary take-up mechanism whereby the timing of the take-up cam readily may be varied relative to the timing of that portion of the stitch-forming mechanism whose thread it controls.

Another object of the invention is to provide improved means to prevent dust, lint and other foreign matter from entering the compartment in the machine frame in which the take-up is mainly located and to prevent the end of the thread from passing into that compartment and becoming entangled with or wound about the take-up or other moving parts in the compartment, should the thread break.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the drawings, Fig. 1 is a front elevation of a two-thread chain-stitch sewing machine embodying the present invention.

Fig. 2 is a right end view, partly in section, of the machine shown in Fig. 1.

Fig. 3 is a vertical sectional view taken substantially on the line 3—3 of Fig. 2.

Fig. 4 is a detail sectional view taken substantially on the line 4—4 of Fig. 3 showing the looper-thread take-up cam and the means for adjustably securing it to a belt-sprocket fixed to the main shaft of the machine.

Referring more specifically to the drawings, the invention is disclosed as embodied in a sewing machine having a frame comprising a base 1, upright standard 2, overhanging arm 3, terminating in a hollow head 4, closed at its forward face by a face-plate 5. The standard is formed with a vertical internal partition 2^a which extends from the bottom wall of the base 1 to the upper wall of the arm 3 and divides the space within the standard into a belt compartment 54 and a splash-lubrication compartment 54^a. This splash lubrication compartment overlies an oil reservoir R in the base 1 and permits the oil therein to be splashed into contact with the working parts therein by the action of a portion of the looper

actuating mechanism therein. The base is formed with upright portions 6 and 8 which support a cloth-plate 9. A guard member or apron 13, hinged on a pin 14 supported by the cloth-plate 9, overlies a portion of the actuating mechanism, designated generally as x, of a chain-stitch looper L, and prevents accidental contact therewith.

Journalized lengthwise within the arm 3 is a main or needle-bar actuating shaft 15, having secured to it, at its rear end, by set screws 15^a, a combined belt- and balance-wheel 16 by means of which the machine may be driven from any suitable source of power. The forward end of the shaft 15 has secured to it a crank-disk 17 carrying a crank-pin 18 connected, by a link 19, with a collar 20, secured upon a hollow needle-bar 21 reciprocably mounted in the head 4. At its lower end the needle-bar carries an eye-pointed needle 22 which cooperates with the looper L in the formation of stitches.

Thread n for the needle passes from a suitable source of supply through a thread-eye 29^x formed in a kink-removing plate 30 (Figs. 1 and 2) secured to a tension-bracket 31 thence around the edge of the plate and back through a thread-eye 29. From the eye 29 the thread extends through a tension 32 thence through a self-threading thread-guide 33, thread-nipper 34, back through the thread-guide 33, through a thread-eye 35 formed in an adjustable arm 36, secured to the machine arm, through a take-up 37, to a thread-eye 38 formed in a plate 39 adjustably secured to the face plate 5, and thence to the eye of the needle.

The looper thread l extends from a suitable source of supply to a thread-eye 40^x formed in a tension-supporting plate 40^y thence through a thread tension 40, through a take-up 41, down through a thread-guiding tube 42, through a thread-guide 43, to the looper L.

The take-up 41 comprises a thread-controlling cam disk 44, adjustably secured to a belt-sprocket 45 fixed upon the main shaft 15. The cam disk 44 is secured to the sprocket 45 by screws 44^a which pass through slots 44^b in the disk and are threaded into the sprocket. The cam disk operates through a slotted stripper-plate 46 carrying a U-shaped thread-stripper 47 and thread-guides 48.

As shown most clearly in Figs. 2 and 3, the belt-sprocket 45 is frictionally secured upon a sleeve 49 which, in turn, is secured to the shaft 15 by means of set-screws 50 and forms a part 55 of a driving connection between the rotary main

shaft 15 and a rotary looper- and lower-feed actuating shaft 51 journaled in bearings provided by the base of the machine. The other elements of the driving connection between the two shafts consist of a similar belt-sprocket 52 secured upon the shaft 51 and a connecting clip-belt 53 surrounding the sprockets. The driving connection between the two shafts is located in the compartment 54, formed in the rear portion of the standard 2, which compartment is normally closed by upper and lower cover-plates 55 and 56, respectively, secured to the standard by screws 57 and 58.

It is sometimes required that the timing of the take-up cam be varied relative to the timing of the looper mechanism. This may readily be effected by adjusting the take-up disk angularly about the axis of the shaft 15. To accomplish this the hand-wheel 16, plate 55, and a cup-like guard element 59 (Fig. 3) which surrounds the shaft 15 and the hub of the sleeve 49 are first removed. After those elements have been removed the screws 44 may be released and the cam-disk rotated slightly about the axis of the shaft after which the screws 44 are again tightened and the guard element, cover-plate and hand-wheel are replaced.

The periphery of the take-up disk 44 projects through a slot 46^a in the take-up stripper plate 46. To prevent dust, lint or other foreign matter from entering the compartment 54 through the slot 46^a and also to prevent the end of the thread from passing into the slot and becoming entangled with or wound about the parts in the compartment 54, should the thread break, means is provided for maintaining, during the operation of the machine, a continuous flow of air outwardly through the slot 46^a, as indicated by the arrows in Fig. 3. This is effected by an air pump preferably in the form of a rotary fan 60 secured to the sprocket 52 on the looper- and feed-actuating shaft 51. During running of the machine the fan 60, which has radially extending and backwardly inclined vanes 61, draws air into the compartment 54 through an opening 62 formed in the cover-plate 56, coaxial with the fan, and forces it upwardly and discharges it through the slot 46^a in the stripper-plate 46.

Having thus set forth the nature of the invention, what I claim herein is:

1. A sewing machine comprising a frame; a needle-bar actuating shaft and a loop-taker actuating shaft journaled therein; a driving connection between said shafts including a sprocket secured to each shaft and a belt connecting said sprockets; a thread take-up mechanism comprising a pair of stationary thread-guides and a rotary take-up disk acting on the thread extending between said thread-guides; and means for adjustably securing said take-up disk to one of said sprockets to permit of angular adjustment of the disk relative to its supporting sprocket.

2. In a sewing machine having a frame provided with a slot in one wall thereof, stitch-forming mechanism, work-feeding mechanism and a take-up mechanism having a portion extending through said slot; the improvement which consists in the provision of means embodied in and actuated by the sewing machine for creating and maintaining a flow of air through said slot and

around and past said take-up mechanism to prevent the accumulation of foreign matter in the region thereof.

3. A sewing machine comprising a substantially closed frame; a rotary shaft journaled therein; a rotary take-up element carried by said shaft and located mainly within said frame but having a portion projecting outwardly therefrom through a slot in a wall of said frame for cooperation with suitable thread-guides; and means for effecting a flow of air outwardly from said frame about said take-up element.

4. A sewing machine comprising a frame having a base, a standard and an overhanging bracket-arm, said standard being formed with a compartment affording a housing for a driving connection; a rotary shaft journaled lengthwise of said bracket-arm and having a portion in said compartment; a second rotary shaft journaled in said base and having a portion in said compartment; a driving connection between said shafts located in said compartment; a rotary take-up disk carried by one of said shafts mainly in said compartment and having a portion projecting outwardly therefrom through a slot in a wall thereof for cooperation with suitable thread-guides; and means actuated by the other of said shafts for effecting a flow of air outwardly from said compartment about said take-up disk.

5. A sewing machine comprising a frame having a base, a standard and an overhanging bracket-arm, said standard being formed with a compartment affording a housing for a driving connection and having an air inlet; a rotary shaft journaled lengthwise of said bracket-arm and having a portion in said compartment; a second rotary shaft journaled in said base and having a portion in said compartment; a driving connection between said shafts located in said compartment; a rotary take-up disk carried by one of said shafts mainly in said compartment and having a portion projecting outwardly therefrom through a slot in a wall thereof for cooperation with suitable thread-guides; and an air pump secured upon the other of said shafts in said compartment for drawing air in through said air-inlet and discharging it through said slot about said take-up disk.

6. A sewing machine comprising a frame having a base, a standard and an overhanging bracket-arm, said standard being formed with a compartment affording a housing for a driving connection and having, adjacent its lower end, an air inlet; a rotary needle-bar driving shaft journaled lengthwise of said bracket-arm and having a portion in said compartment; a rotary looper-actuating shaft journaled in said base and having a portion in said compartment; a driving connection between said shafts located in said compartment; a rotary take-up disk carried by said needle-bar driving shaft and located mainly in said compartment and having a portion projecting outwardly therefrom through a slot in a wall thereof for cooperation with suitable thread-guides; and a vane type fan secured upon the said looper-actuating shaft in said compartment for drawing air in through said air-inlet and discharging it through said slot about said take-up disk.

ANDREW B. CLAYTON.
